CLAIM

The ornamental design for a resistance exercise trainer, as shown and described.

DESCRIPTION

FIG. 1 is a perspective top view of the design;

FIG. 2 is a perspective view thereof with broken lines depicting environment;

FIG. 3 is a front view thereof;

FIG. 4 is a side view thereof; and,

FIG. 5 is a rear view thereof.

The broken line showing of portions of the resistance exercise trainer depicts environment and forms no part of the claimed design.

1 Claim, 5 Drawing Sheets(56)
